Primary Examiner — Janice Patyk*(74) Attorney, Agent, or Firm* — LEASON ELLIS LLP(57) **CLAIM**

The ornamental design for a speaker device with lights, as shown and described.

DESCRIPTION

FIG. 1 is a top perspective view of a speaker device with lights showing my new design, shown in an illuminated state;

FIG. 2 is a bottom perspective view thereof;

FIG. 3 is a front elevational view thereof;

FIG. 4 is a rear elevational view thereof;

FIG. 5 is a right-side elevational view thereof;

FIG. 6 is a left-side elevational view thereof;

FIG. 7 is a top plan view thereof; and,

FIG. 8 is a bottom plan view thereof.

The broken lines in the figures illustrate the portions of the design that form no part of the claimed design.

1 Claim, 8 Drawing Sheets(56)
